DEPOSITING MACHINE

Robert J. Oswalt, Danville, Ill., assignor to Fred W. Amend Co., Danville, Ill., a corporation of Illinois

Application January 18, 1940, Serial No. 314,377

5 Claims. (Cl. 107—1)

My invention relates to improvements in depositing machines for use in making candy, confections, and the like. It comprises an auxiliary feeding hopper which can be inserted into the usual feeding hopper of a depositing machine, with detachable pipes being connected thereto and to the usual outlets from the main hopper whereby confection of different colors or kinds can be simultaneously deposited in pre-prepared molds.

I am aware that machines of this type have heretofore been used in the art, but they are unitary structures and adapted to do only one particular job. These depositing machines are quite expensive and in many instances to have a machine for one special purpose is prohibitive insofar as the cost of the machine is concerned and adds materially to the cost of the confection to be manufactured. With my improved construction I am able to use the standard machine for depositing candy or confection of one kind in single units, and by adding my attachment thereto the machine is converted so that multiple kinds of confection can be deposited simultaneously in the same mold. When desired, the attachment is removed and the depositing machine utilized for the single purpose for which it was originally intended. In this manner the purchase of additional machines, which of necessity must stand idle for a good portion of the time when not making special kinds of confection, is unnecessary, and the investment expense of manufacture is materially reduced, floor space is saved, additional labor costs are avoided, and the expense of production of the particular product is also materially reduced.

Another and further object of my invention is the provision of means which can be easily and quickly attached to the hopper of an ordinary depositing machine as well as removed therefrom, and the parts of which are simple to manufacture and easy to clean in preparation for use and after they have been used.

These and other objects of my invention will be more fully and better understood by reference to the accompanying drawings, in which—

Figure 1 is a top plan view partially in section of the standard depositing machine with my invention applied thereto;

Figure 2 is a rear view of the pump with plate attached, forming a part of the usual standard machine;

Figure 3 is a transverse sectional view of the machine with the auxiliary hopper attached;

Figure 4 is a top plan view of a depositing machine showing means for supplying three different kinds of confection to the depositing pump; and

Figure 5 is a transverse sectional view of the apparatus illustrated in Figure 4.

Referring now specifically to the drawings and in which like reference characters refer to like parts throughout, a main hopper 10 is shown having a curved bottom 11, end walls 12 and 13, 10 and a front plate 14 usually of cast material, the balance of the hopper being made of sheet metal of any preferred form. The plate 14 at the bottom thereof has a pump casing 15 extending throughout the length of the hopper plate 14 15 upon which cylinders 16 are mounted, having pistons 17 therein, the combination acting as pumps for depositing the material in fluid form in pre-formed molds, and with a plate 18 at the rear side thereof having openings 19, 19 there- 20 in which are in register with outlet openings in the front wall 14 of the hopper 10. All of these parts are of standard construction for depositing machines and are used for depositing fluid material in the making of candy and various 25 confections in predetermined quantities, usually in pre-formed starch molds which are advanced on suitable carriers underneath the outlet spouts of the pumps in step by step relation and in synchronism with the operation of the pumps, all 30 of which is old and well-known in the art and it is not deemed necessary to here illustrate or describe.

The machines hereinabove described are adapted for making only one kind or one color of 35 a particular candy or confection at a time. If it is desired to make a two-color piece of confection or a confection composed of two kinds of materials it has been necessary heretofore to use a machine with a plurality of discharge spouts 40 with the hopper separated by partitions or the like to contain the materials ultimately deposited in the molds.

My improvement comprises an auxiliary hopper 20 of a size and shape to fit inside of the 45 main hopper 10 while still allowing sufficient space for material to be placed in the main hopper 10. The auxiliary hopper 20 is provided with a handle 21 for convenient handling and with brackets 22, 22 which engage the upper edge of 50 the end walls 12 and 13 of the main hopper 10 so that the auxiliary hopper 20 is held suspended in the main hopper 10. The hopper 20 is somewhat narrow at the bottom so that when filled or partially filled with material it will be sus- 55

pended in a vertical direction in the main hopper 10, as shown particularly in Figure 3. Outlets ports in spaced relation with each other are provided in the forward front wall of the hopper 20, to which flexible tubes 23, 23 are connected. These tubes 23 have metallic end members 24, 24 with collars 25, 25 spaced inward from the ends of the tubes a slight distance and securely fastened to the tubes 23. Gaskets 10 26, 26 are provided which contact against the outer front wall of the hopper 20 and the inner side of the front wall 14 of the main hopper 10. The ends of these tubes 23 project through the ports in the auxiliary hopper 20 and the ports 15 in the front wall 14 of the main hopper, and into the pump casing 15. These tubes, being flexible, are also expansible and when placed in position are slightly compressed so that the gaskets 26 are held firmly against these walls without 20 danger of the material leaking therefrom, and form tight openings from the outlet ports to the pump. The ports in the auxiliary hopper are preferably in register with each alternate port in the row of outlet ports in the front wall 14 25 of the hopper 10, and in this manner one kind of confection is supplied to the pumps from the main hopper 10 while another kind is supplied from the auxiliary hopper 20.

In pre-forming the molds for the reception of 30 the deposited material making up the finished piece of candy or other confection, I prefer to make the receiving recesses in the molds slightly elongated so that each mold passes under the outlet spouts of two pumps. In this manner the 35 material is deposited somewhat toward the end of each of the pre-formed receiving recesses in the molds and flows outward toward the ends and inward toward the center with a blending of the material at the center of the mold. Thus, 40 if it is desired to form a confection, such as a piece of candy, with an orange color at one end and a lemon yellow at the other, one kind of material is placed in the main hopper and the other placed in the auxiliary hopper and simultaneously 45 deposited in the mold, so that as it flows into the mold the final confection is a two colored piece, the ends of which are distinct as far as the original colors are concerned, while there may be a slight blending along the middle 50 line of the piece of confection but insufficient to destroy the clear line of color distinction.

In Figures 4 and 5 is illustrated a modified form 55 of my improved invention. An auxiliary hopper 27 is provided of substantially the same shape and contour as the hopper 20 heretofore described, but with a middle wall 28 extending longitudinally thereof whereby the hopper 27 is divided into compartments 29 and 30. The wall of the hopper 27 has a plurality of spaced outlet ports therein in alignment with pairs of the spaced ports in the front wall 14 of the main hopper, while each alternate discharge port leading from the hopper 27 has a short tube 31 spanning the distance from the front wall of the hopper 27 to the bottom of the partition 28, so that material from the compartment 30 flows through the short fixed tubes 31 and through the outlet tubes 23, 23 to the pump frame 15. The material from the compartment 29 flows 60 directly into the outlet tubes 23 and is conveyed therethrough to the pump casing 15. Three compartments are thus provided, two in the auxiliary hopper 27 and one in the main hopper 10 so that three different kinds of material or three 65 different colored materials of the same kind and

character can be placed in the three compartments of the hopper and simultaneously deposited in the starch molds in the regular operation of the machine. In this fashion a three colored piece of confection can be easily and quickly 5 produced, such as red, white and blue for sale around the Fourth of July, and other confections for other seasonable times of the year or for regular sale if so desired.

The operation and use of these auxiliary hoppers will be readily understood from the foregoing description, in that when it is desired to produce a single confection made up of two materials or two different colored materials, the hopper illustrated in Figures 1, 2 and 3 may be used 15 and the materials kept separated until they are finally deposited in the molds as they pass underneath the discharge spouts of the pump. When a run of this material is finished the auxiliary hopper may be removed and the machine 20 continued in use for depositing a single kind or single color confection, as may be desired.

In the form illustrated in Figures 4 and 5 the operation is precisely the same except that the hopper 27 is placed inside the main hopper 10, 25 with the discharge spouts suitably connected to the outlet ports in the main hopper 10 in any way that may be desired, it only being necessary to provide that the molds are sufficiently large to extend under at least three of the discharge 30 spouts from the pump.

The auxiliary hoppers and the connecting parts can be added to or removed from a machine in a short space of time and easily kept clean for use any time that may be desired.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

What is claimed is:

1. In combination with a candy making machine, a main hopper having a plurality of spaced discharge ports at the bottom thereof, an auxiliary hopper having a plurality of spaced discharge ports fitted into and removable from the main hopper, and a plurality of connections leading from the ports in the auxiliary hopper to selected discharge ports in the main hopper. 45

2. In combination with a candy making machine, a main hopper having a plurality of spaced discharge ports at the bottom thereof, an auxiliary hopper having a plurality of spaced discharge ports removably supported in the main hopper, and a plurality of connections leading from the ports in the auxiliary hopper to selected discharge ports in the main hopper. 55

3. In combination with a candy making machine, a main hopper having a plurality of discharge ports at the bottom thereof, a plurality of pumps corresponding in number with said discharge ports, an auxiliary hopper having a plurality of discharge ports at the bottom thereof, and flexible connectors leading from the discharge ports in the auxiliary hopper through selected discharge ports of the main hopper to the said pumps. 65

4. In combination with a candy making machine, a main hopper having a plurality of discharge ports at the bottom thereof, a plurality of pumps corresponding in number with said discharge ports, an auxiliary hopper having a 70

plurality of discharge ports at the bottom thereof, flexible connectors leading from the discharge ports in the auxiliary hopper through selected discharge ports of the main hopper to the said pumps, and brackets supporting the said auxiliary hopper in the main hopper.

5. In combination with a candy making machine, a main hopper having a plurality of discharge ports at the bottom thereof, a plurality

of pumps corresponding in number with said discharge ports, an auxiliary hopper having a plurality of compartments therein having a plurality of discharge ports at the bottom thereof from each compartment, and flexible connectors leading from the discharge ports in each of the compartments through selected discharge ports of the main hopper into the said pumps. 5

ROBERT J. OSWALT.
